UNITED STATES PATENT OFFICE.

ADOLPHE PAROUTAUD, OF NEW YORK, N. Y.

DESIGN FOR A COVERED DISH.

SPECIFICATION forming part of Design No. 29,816, dated December 20, 1898.

Application filed November 16, 1898. Serial No. 696,647. Term of patent 3½ years.

To all whom it may concern:

Be it known that I, ADOLPHE PAROUTAUD, a citizen of the United States, residing in the city of New York, borough of Manhattan, in the county and State of New York, have invented and produced a new and original Design for a Covered Dish, of which the following is a specification, reference being had to the accompanying drawings, forming a part thereof, in which—

Figure 1 is a plan view of a covered dish embodying the features of my design, and Fig. 2 is a side elevation of the same.

The leading feature of the design consists in the contour of the body A and the contour and decorations of the cover B.

The body is given an exteriorly plain contour, flaring outwardly and upwardly in a curved line of large radius from the base b, the base being given a downward and outward inclination and provided with a scalloped lower edge, the scallops being alternately long and

short. Rustic handles C are provided for the ends of the body, and the base is given linear and point decorations.

The cover B is of a scalloped peripheral contour, the scallops being alternately long and short, and the upper face of the cover rises upwardly from the periphery in a slight degree to a point b', from which point the exterior surface of the cover rises gradually upward to a greater degree to the crown, which crown portion is provided with a rustic handle B'. The cover is further decorated with a scalloped doily figure b², appearing around and below the handle of the cover.

I claim—

The design for a covered dish herein shown and described.

A. PAROUTAUD.
